JOHN E. PRINTY, OF TUCSON, ARIZONA.

BRAKE-SHOE.

1,264,142.

Specification of Letters Patent.

Patented Nov. 5, 1918.

Application filed March 29, 1918. Serial No. 225,530.

To all whom it may concern:

Be it known that I, JOHN E. PRINTY, a citizen of the United States, residing at Tucson, in the county of Pima and State of Arizona, have invented certain new and useful improvements in Brake-Shoes, of which the following is a specification.

This invention relates to brakes, and more especially to removable shoes therefor; and the object of the same is to produce an improved means for connecting the shoe with the brake block so that as far as possible the generation of dust may be prevented.

Details are set forth below, and reference is made to the drawings, wherein:—

Figure 1 is a side elevation,

Fig. 2 is a rear edge view,

Fig. 3 a vertical section on the line 3—3 of Fig. 2,

Fig. 4 is a rear edge view of the facing removed, and

Figs. 5 and 6 horizontal sections on the lines 5—5 and 6—6 of Fig. 1.

The brake block 1 is provided with holes or eyes 2 and 3 for receiving the links or other devices (not shown) by means of which this block is suspended from the brake beam in a manner not necessary to amplify in the present specification. Also it will not be necessary herein to detail means for actuating the beam to apply the brake and to release it. However, to those familiar with railway brakes, it is well known that if the cars of a train should become separated accidentally the brakes are applied with service application instead of emergency. In my experience dust gets into the triple valve and prevents or retards the slide from working, with the result that often when the brakes are set they will not release and the casing of the triple valve must be tapped with a hammer or the like, thereby resulting in great annoyance. The object of the present invention is more particularly to produce a brake shoe in which the generation of dust is minimized, and by means of which such dust as is raised is allayed. Moreover, it is well known that the facing or lining of brake shoes wears away and in time must be replaced, and this necessity also has been taken into consideration. The front face 4 of the

block 1 is preferably dished as seen in Fig. 1, being struck on a continuous arc from its lower end upward, but its upper end is flattened as shown at 5; and this face is provided with an upright groove 6 dove-tailed in cross section and tapering downward as seen in dotted lines in Fig. 2, the groove at its upper end running out through the flat face 5.

The facing or lining 10 has its front or active face dished as indicated at 14 and its rear face curved to conform with the dished face 4 of the block, said rear face being preferably inclined forward at its upper end as indicated at 15 in a plane intersecting said curve. The rear face of the facing carries a dove-tailed tongue 16 tapering downward as best seen in Fig. 4, and the tongue 16 is intended to fit the groove 6. The downward taper of these elements prevents the facing from dropping off the block, because when the tongue is put into the groove and the facing is moved downward until the parts fit closely, the facing can obviously go no farther. At this time registering notches 17 across the base of the groove and the rear wall of the tongue will produce a transverse opening, and through the same a pin 18 is driven as best seen in section in Fig. 3 and in plan in Fig. 6. This pin positively prevents the accidental rise of the facing, which is its tendency when the brake is applied while the car is being backed. When the facing is to be replaced, the pin is first withdrawn and then by a gentle tap on the lower end of the facing the tongue is loosened from the groove and it may be readily moved upward and a new facing put in its place. The parts are of the desired proportions and materials, and I reserve the right of making the facing of such material and of such shape that it will generate as little dust and produce as little wear on the tread of the wheel as possible.

What is claimed as new is:—

In a brake shoe, the combination with a block having its front face dished on an upright curve and the upper portion thereof flattened, said face being provided with an upright groove of dove-tailed cross section running out in the flattened face and taper-

ing downward; of a facing having its rear face struck on a curve to correspond with said dished face, its upper portion being flattened in a plane intersecting said curve, 5 and a tongue on said curved rear face, this tongue being of dove-tailed cross section and tapered to fit said groove.

In testimony whereof I affix my signature in presence of two witnesses.

JOHN E. PRINTY.
